UNITED STATES PATENT OFFICE.

ELZA R. HURST, OF ORIENT, OHIO.

GATE.

1,111,901.

Specification of Letters Patent. Patented Sept. 29, 1914.

Application filed April 7, 1914. Serial No. 830,137.

To all whom it may concern:

Be it known that I, ELZA R. HURST, a citizen of the United States, residing at Orient, in the county of Pickaway and State of Ohio, have invented certain new and useful Improvements in Gates; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in automatically operated gates and especially in the provision of a tilting gate and automatic latch so arranged that, when the gate is closed, it automatically locks and the initial raising movement of the gate preparatory to its rolling to an open position will allow the latch to be released.

My invention comprises various details of construction, combinations and arrangements of parts which will be hereinafter fully described, shown in the accompanying drawings and then specifically defined in the appended claims.

I illustrate my invention in the accompanying drawings, in which:

Figure 1 is a side elevation of the gate showing the gate closed in solid lines and open in dotted lines. Fig. 2 is a front elevation of the gate closed. Fig. 3 is an enlarged detail view of the gravity latch, Fig. 4 is an enlarged detail view showing the latch released from a catch, and Fig. 5 is a detail view showing the latch closed, the post being illustrated in section.

Reference now being had to the details of the drawings by letter, A, A designate posts which have a rod B connecting the same and upon which the upper ends of the bars B' are pivoted and which latter are pivotally connected as at B² to the angled tracks C at the longitudinal centers thereof. Levers, designated by letter D, are pivotally mounted upon the pins D' carried by the bracket members E which are fastened to the post or standard and the inner end of each lever has loose pivotal connections with the curved rod F which is fastened to the upright portions of the tracks as shown. Rods F are pivotally connected to the outer ends of the levers and their lower ends piv-

otally connected to the angle plates H which are pivoted at H' to the bracket members H², fastened to the post. Rods I are pivotally connected one to the lower end of each angle plate and the other end to the horizontally disposed crank shaft J having two offset portions K and K' over which the wheels of a vehicle are adapted to move when traveling in one direction or the other accordingly as it may be desired to cause the gate to be opened or closed.

The gate, designated by letter N, has two end posts O carrying bracket members O', each of which is provided with a laterally extending stub shaft Q carrying a wheel R' which is adapted to travel upon said tracks. A chain, designated by letter M, is fastened at one end to the rear post of the gate and its other end to the tilting track and is adapted to limit the movement of the gate in one direction to prevent the gate moving over the track when rolling to an open position. An angled post, designated by letter T, is provided with a central slot T' at its apex and the slot has a widened portion above the shoulders T².

A gravity latch, designated by letter L, is pivotally mounted in a hole in the front post of the gate and has its forward end L' bent to form a hook and to its opposite end a weighted arm L² is fixed, the purpose of said arm being to normally hold the hook at an inclination to the slot in said post so that, when the gate closes, the end of the hook striking the adjacent face of the angled slotted post will cause the hook to tilt to allow the hook to pass through the slot, after which the weighted arm will return the hook to its normal position and throw the hook into a locked relation over the edge of the slot, as shown clearly in the drawings.

The operation of my invention will be readily understood and is as follows: When it is desired to open the gate, a vehicle approaching from either position and driving over one of the loops of the crank shaft may cause one or the other of the levers to be actuated to tilt the forward end of the track upward, which will cause the gate to roll by gravity to an open position. Prior to the opening of the gate, it will be necessary to release the hook from said angled post. This is accomplished during the initial operation in opening the gate, the first movement, as one or the other of the levers is

tilted, causing the forward end of the gate to be raised a sufficient distance to allow the hook to pass through the widened portion of the slot without interference with the marginal edges of the slot. A further tilting movement of the gate will cause the latter to roll by gravity to an open position. When it is desired to close the gate by a vehicle passing from either direction over another 10 loop of the crank shaft, the angled track will be tilted back to its normal position and the gate will roll by gravity to its closed position and, as the hook which is normally disposed at an inclination, comes in contact 15 with the inclined edge of the angled post, the momentum of the gate will cause the shank portion of the hook to rock to allow the hooked end to pass through the slot and, after the hook has passed through the slot, 20 the weighted arm will return the hook to its normal position to engage over the edge of the slot.

From the foregoing, it will be noted that, 25 by the provision of a gate made in accordance with my invention, a simple and efficient mechanism is afforded whereby the gate is not only released automatically but opened, closed and locked by a vehicle approaching the gate in either direction.

30 What I claim to be new is:

1. A gravity gate and automatic lock comprising posts, angled tracks pivotally mounted thereon, means for tilting the tracks, a gate having rollers mounted upon said 35 tracks, a vertically disposed V-shaped post having a slot in the ridge thereof, which slot is widened near its upper end, a latch journaled in the gate post and having one end hooked and a counterbalance arm upon the 40 other end, said hook adapted, as the gate closes, to contact with the inclined face of

the gate post to cause the gate to lock under the momentum of the gate closing, and a gravity arm throwing the hook over the edge of the slot after the hook passes 45 through the latter, said gate being adapted to be raised at its latch end so as to permit the latch to pass freely through said widened portion of the slot when the tracks are rocked to open the gate, as set forth. 50

2. An automatically operated gate comprising a post, angled tracks pivotally mounted between the same, levers pivotally mounted upon the posts and having their inner ends apertured, a rod fastened to the 55 tracks and having loose pivotal connection with said apertures, horizontally disposed rock shafts with pivotal connections between the same and said levers, a gate having rollers at the upper ends thereof mounted upon said tracks, a chain fastened to one end of the gate and the other end to the track to limit the movement of the gate in one direction, a slotted V-shaped post, a hook having a shank portion journaled in 60 the end of the gate, one end bent to form a hook for engagement with a slot in said post, and a weighted arm upon the other end of the hook, the upper portion of the slot being widened to allow the hook to withdraw when in its normal position, said gate being 65 adapted to be raised at its latch end so as to permit the latch to pass freely through said widened portion of the slot when the tracks are rocked to open the gate, as set forth. 70

In testimony whereof I hereunto affix my signature in the presence of two witnesses.

ELZA R. HURST.
